WINDOW CONSTRUCTION

Oliver M. Edwards, Syracuse, N. Y., assignor to
 The O. M. Edwards Company, Inc., Syracuse,
 N. Y., a corporation of New York

Application February 4, 1937, Serial No. 124,064

10 Claims. (Cl. 189—64)

This invention relates to window constructions, particularly useful in motor vehicles, as buses, railway cars, and the like, and more particularly to double sash windows, wherein there is an air space between the glass panes.

It has for its object a window construction wherein a dehydrating or moisture absorbing material is used to absorb the moisture from the air between the glass panes of the sashes to avoid clouding, and a construction wherein the dehydrating material is readily removable and replaceable with fresh material.

It further has for its object a double sash construction, wherein the sash sections abut against each other in air-tight relation, and one of the sections is demountable and provided with a channel opening into the space between the glass panes of the sash sections for receiving a dehydrating material, preferably a granular dehydrating material, so that when the demountable sash is removed, the dehydrating material may be readily removed from the channel and replaced with fresh material.

It further has for its object the sash construction and the sash and window frame construction hereinafter set forth.

The invention consists in the novel features and in the combinations and constructions hereinafter set forth and claimed.

In describing this invention, reference is had to the accompanying drawings in which like characters designate corresponding parts in all the views.

Figures 1 and 2 are fragmentary front and rear elevations of this window construction.

Figure 3 is an enlarged sectional view on line 3—3, Figure 1.

Figure 4 is an enlarged fragmentary sectional view of parts seen in Figure 3.

Figure 5 is a view similar to Figure 3 of a slightly different form of the invention.

Figure 6 is a fragmentary view, partly in section, of one of the lower corners of the demountable sash section shown in Figure 5.

1 designates the window frame, this being usually formed of metal and of such shape as to form a lining for the window opening in the body of the vehicle, that here shown having an outwardly extending circumferential flange 2 on the inner side of the frame, that is, the side toward the interior of the vehicle, for lapping the wall of the body around the window opening and form a facing therefor. The window frame 1 is also formed with an inwardly extending abutment or

flange 3, this being inset from the outer edge of the frame.

4 and 5 are the inner and outer sections of a double sash frame, each of which carries a glass pane 6 or 7 which is spaced apart to provide an air space between them. The outer section is formed with a circumferential flange 8 opposed to one side of the abutment 3 and with a channel 9 on its inner side, this channel being also open on the side toward the inner section 4. The section 5 is also formed with an outwardly extending circumferential flange 10 opposed to the flange 2 and forming a facing for the margin of the wall around the window opening. The mounting for the glass pane 7 is located in the channel 9, and this mounting is of a resilient compressible material, as rubber, and includes a channel shaped frame 9a of rubber or other suitable material for receiving the margin of the glass pane 7 and a backing 12 of rubber extending circumferentially around the frame 9a and seating in the channel 9. It serves to cushion the fixed frame 5 against shocks and relieve the glass pane of undue strains.

The backing 12 interlocks with the mounting 9a for the glass pane 7, and as here shown, this mounting is formed with a peripheral circumferential groove in which the backing 12 interlocks or seats. The backing 12 is held from displacement out of the channel 9 on the open side of the channel toward the inner section 4 by a lip 30 9b along the inner edge of the bottom of the channel 9 and a shoulder 9c (Figure 4) on the backing 12, which is caught on the lip 9b. This construction holds the outer section 5 from unintentional displacement when the inner section 4 is demounted.

The outer section 5 is secured to the window frame by fastening members, as screws 13, extending through the abutment 3 and threading into the flange 8 of the frame section 5, the heads of the screws being located toward the inner side of the window frame or on the same side that similar fastening screws are provided for holding the demountable frame 4 in the window frame, so that the screws are accessible when the frame 4 is demounted.

The inner frame section 4 is provided with a body flange opposed to and spaced from the abutment 3 and also with a channel 14 for receiving the margin of the glass pane 6 and a resilient 50 marginal frame or packing 15. One side 16 of the channel 14 is demountable or is a removable glazing strip.

One of the frame sections, preferably the section 4, is also formed with a spacer rib 17 extend- 55

ing into the space between the glass panes and abutting against the backing for the pane 7. The rib is formed with a channel 18, particularly in the lower rail thereof for receiving a dehydrating or moisture absorbing material. This material is granular and hence can be easily removed and replaced, when the sash frame 4 is removed. The material used is known commercially as activated alumina.

10 The frames 4 and 5 are usually formed by an extruding process and the channel 18 for economy in manufacture, is formed throughout the entire extent, with the rib 18, although the channel along the lower rail of the rib is preferably the one utilized for holding the dehydrating material, as no means is necessary for retaining it in the channel. The material used is effective to absorb moisture for a period of six months, more or less. The dehydrating qualities of the material are well known.

15 The inner frame 4 is secured in position and clamped against the resilient backing for the inner glass pane 7 by fastening members, as screws 20, extending through the inner frame 4 and threading into the abutment 3.

20 When the window is provided with a curtain roller, the curtain roller is located in line with or at the level of the upper rail of the sash 4 instead of above the sash frame, so that the curtain roller can be used without requiring extensions of the window frame 4 in an upward direction, or so that a window frame with a curtain can be mounted in the same window opening as a window frame without a curtain.

25 35 designates a curtain roller and 23 the curtain thereon, which has a suitable fixture 24 at its free end for running in curtain guides 25 formed in the uprights of the window frame 4. The curtain roller 22 is suitably mounted in a box or housing 26 mounted in the window frame 40 beneath the upper rail thereof in a horizontal line with the upper rail of the sash section 4.

30 45 The top wall of this box or housing abuts squarely against the top rail of the window frame and the end walls 27 thereof are formed with openings for receiving pins 28 on the uprights of the window frame, the pins snapping into openings in the holes in the end walls. The curtain roller is suitably mounted between the end walls 27.

40 50 55 In Figure 5, a rib 37 corresponding to the rib 17 is formed with a channel 38 corresponding to the channel 18 for receiving the dehydrating material, which is packed in the form of a rod or in a perforated tube. The channel is formed with a contracted entrance at 39, and in order that the rod may be slid into the channel 38, the channel opens at 40 through the bottom of the channel of one of the uprights of the demounted section of the sash. The opening at 40 is closed after the rod has been inserted by a plug 41. Also, in Figure 5, the curtain roller 42 corresponding to the roller 22 is shown as mounted in the window frame above the window sash in a box or housing 46 suitably secured in the window frame. In the construction shown in Figure 5, the upper rail 47 of the window frame is formed angular in cross section to provide a recess for the curtain roller and its housing, and the inner upright wall 47^a of the rail 47 terminates in the abutment or flange 48 corresponding to the abutment or flange 3 (Figure 3). Also, a hinge plate or strip 49 is provided along the upper rail of the inner sash section 4 and located between said upper rail of the inner sash section

4 and located between said upper rail and the wall 47^a of the top rail 47 of the window frame, it interlocking with or hooking over the rib 50 on the wall 47^a. The two sash sections 4, 5 are secured, in Figure 5, to the abutment 48, the same as in Figures 3 and 4, except that the hinge plate 49 is employed in Figure 5. The hinge plate permits the inner sash section 4 to swing open instead of entirely demounting it. It may be demounted however by lifting it slightly to 10 unhook the strip 49 from the rib 50, after the sash section 4 has been swung outward.

15 Owing to the construction shown in either Figures 3 or 5, the inner frame 4 can be readily removed by freeing the screws 20 of the abutment 3 and the dehydrating material removed and replaced with a fresh supply, and when the demountable frame section is replaced, tightening of the screws 20 clamps the rib 17 against the resilient backing for the outer glass pane 7, 20 thus sealing the space between the glass panes 6 and 7. Also, when the outer frame section 4 is removed, the inner glass pane 7 and its mounting may be removed, if necessary, as for reglazing.

What I claim is:—

25 1. In a window construction, a double sash comprising inner and outer frame sections, one of the sections being demountable and formed with a channel opening into the space between the glass panes of the double sash, for receiving a readily removable moisture absorbing material in the channel, and means for clamping the demountable section against the other section in sealed relation thereto.

30 2. In a window construction, a window frame, a double sash mounted in the frame and comprising inner and outer frame sections, one of the sections being demountable and the other section being fixed and having a resilient mounting for its glass pane, extending between the sections and against which the demountable section is pressed, means for securing the fixed section to the frame, the demountable section having a spacer portion pressing against said resilient mounting, and means for securing the demountable portion to the window frame independently 40 of the fixed section.

35 3. In a window construction, a window frame, a double sash mounted in the frame and comprising inner and outer frame sections, one of the sections being demountable and the other section being fixed and having a resilient mounting for the glass pane extending between the sections, means for securing the fixed section to the frame, the demountable section having a spacer portion pressing against said resilient mounting, and means for securing the demountable portion to the window frame independently 50 of the fixed section, said spacer portion being formed with a channel opening into the space 55 between the glass panes of the sash sections, for receiving a moisture absorbing material.

40 4. In a window construction, a window frame formed with an inwardly extending abutment, a double sash mounted in the frame and including sections on opposite sides of said abutment, one section being fixed and the other demountable, the fixed section being formed with a resilient backing for the glass pane and the demountable section being formed with a circumferential spacing rib thrusting against the resilient backing, said rib being formed with a channel opening into the space between the glass panes, for receiving a moisture absorbing material, screws extending through the abutment and 70 75

into the fixed section for securing the fixed section in the window frame and having their heads accessible from the side of the abutment toward the demountable section, and screws extending through the demountable section and into the abutment.

5. In a window construction, a window frame, a double sash supported by the frame and comprising inner and outer frame sections, each section including a glass panel unitary with the section, means for mounting one of the sections in the window frame independently of the other sash section, whereby the latter section is demountable from the former section, and means 10 coacting with the window frame for clamping the other section with its glass panel against the former section.

6. In a window construction, a window frame formed with an inwardly extending abutment, 20 a double sash comprising inner and outer sections, and a glass panel carried by each section as a unit therewith, the sections being arranged on opposite sides of said abutment, one of the sections and its panel being demountable, means 25 for securing the sections to the abutment independently of each other, the means for securing the demountable section to the abutment serving to clamp the demountable section against the other section.

30 7. In a window construction, a window frame formed with an inwardly extending abutment, a double sash comprising inner and outer sections, each section including a glass panel unitary therewith, the sections being arranged on opposite sides of said abutment, one of the sections and its panel being demountable as a unit, means for securing the sections to the abutment independently of each other, the means coacting with the abutment for clamping the demountable section against the other section being accessible from the same side of the abutment as the securing means for the said other section.

8. In a window construction, a window frame, a double sash mounted in the frame and comprising inner and outer sections, one section being mounted in the window frame and having a resilient circumferential member for its glass pane extending between the sections, the other section being demountable, and means for securing the demountable section to the window frame and pressing it against the resilient circumferential member of the former section, one 10 of the sections being formed with a channel opening into the space between the glass panes of the sash sections for receiving a moisture-absorbing material.

9. In a window construction, a double sash 15 comprising inner and outer frame sections, one of the sections being demountable and one of the sections being formed with a channel opening into the space between the glass panes of the double sash for receiving a readily removable 20 moisture-absorbing material, and means for clamping the demountable section in sealed relation to the other section.

10. In a window construction, a window frame, a double sash frame comprising two sections, a 25 glass panel having a resilient circumferential member mounted in one section, the circumferential member being formed with a channel for receiving the panel, the other section having means for supporting its glass panel, the latter 30 section abutting against one side of the resilient circumferential member for the former glass panel, and means for securing the latter section to the window frame and clamping it against a resilient circumferential member mounted on 35 the former section, and means for securing the former section in the window frame independently of the latter section, whereby the latter section can be demounted leaving the former section in place.
